COMBINED CARRYING HANDLE AND VALVE
ACTUATING UNIT FOR A PORTABLE FIRE
EXTINGUISHER OR SIMILAR ARTICLE

Robert H. Hose, Mountainside, and George L. Payne,
South Brunswick Township, Middlesex County, N.J.

Application March 16, 1959, Serial No. 55,018

Term of patent 14 years

(Cl. D16—2)

Fig. 1

Fig. 2

Fig. 1 is a front elevational view of a combined carrying handle and valve actuating unit for a portable fire extinguisher or similar article, with a portion of the discharge nozzle being shown in section, embodying our new design;

Fig. 2 is a top plan view thereof, the bottom not shown being substantially plain;

Fig. 3 is a left side elevational view thereof; and

Fig. 4 is a right side elevation view thereof, with a portion of a housing for a pressure gauge being shown in section to illustrate the gauge case and the gauge glass.

We claim:

The ornamental design for a combined carrying handle and valve actuating unit for a portable fire extinguisher or similar article, substantially as shown and described.
